UNITED STATES PATENT OFFICE.

WESLEY N. ONDERDONK, OF UTICA, NEW YORK.

DESIGN FOR A STEERING-POST SUPPORT FOR AUTOMOBILES.

53,517.

Specification for Design.

Patented July 8, 1919.

Application filed February 14, 1919. Serial No. 277,106. Term of patent 7 years.

To all whom it may concern:

Be it known that I, WESLEY N. ONDERDONK, a citizen of the United States, residing at Utica, in the county of Oneida and State of New York, have invented a new, original, and ornamental Design for a Steering-Post Support for Automobiles, of which the following is a specification, reference being had to the accompanying drawings, forming part thereof.

Figure 1 is a front view of the design; Fig. 2 is a rear view thereof; and Fig. 3 is a perspective view of the design.

I claim:

The ornamental design for a steering post support for automobiles, as shown.

WESLEY N. ONDERDONK.
